UNITED STATES PATENT OFFICE.

RAYMOND H. VERMILLION, OF LOS ANGELES, CALIFORNIA, ASSIGNOR TO H. L. JUDD COMPANY, INC., OF WALLINGFORD, CONNECTICUT, A CORPORATION OF DELAWARE.

DESIGN FOR A DRAPERY-POLE END OR SIMILAR ARTICLE.

Application filed April 10, 1928. Serial No. 26,223. Term of patent 3½ years.

To all whom it may concern:

Be it known that I, RAYMOND H. VERMILLION, a citizen of the United States, residing at Los Angeles, in the county of Los Angeles and State of California, have invented a new, original, and ornamental Design for a Drapery-Pole End or Similar Article, of which the following is a specification, reference be-

ing had to the accompanying drawing, forming part thereof.

The figure is a front elevation of a drapery pole end, showing my new design.

I claim:

The ornamental design for a drapery pole end or similar article, as shown.

RAYMOND H. VERMILLION.
